Primary Examiner — Freda S Nunn(74) *Attorney, Agent, or Firm* — Saidman DesignLaw Group, LLC(57) **CLAIM**

The ornamental design for a machine display, as shown and described.

DESCRIPTION

FIG. 1 is a perspective view of a machine display showing our new design;

FIG. 2 is a front view thereof;

FIG. 3 is a rear view thereof;

FIG. 4 is a right side view thereof, the left side being a mirror image thereof;

FIG. 5 is bottom view thereof;

FIG. 6 is a top view thereof; and,

FIG. 7 is an enlargement of the encircled area in FIG. 1. The dashed broken lines illustrate environmental structure and form no part of the claimed design.

The dot-dash broken lines encircle areas of enlargement. The drawings include surface shading that represents contour and not surface ornamentation.
